Williamson Reiff Williamson

UNITED STATES PATENT OFFICE.

CARL S. CARLBERG, OF MOUND, MINNESOTA, ASSIGNOR, BY DIRECT AND MESNE ASSIGNMENTS, TO PRESSTEEL RADIATOR COMPANY, A CORPORATION OF MINNESOTA.

RADIATOR.

Application filed April 12, 1926. Serial No. 101,316.

This invention relates to radiators for heating the interiors of buildings.

The invention is an improvement upon my invention disclosed in an application for 5 U. S. Letters Patent entitled "Radiator", Serial Number 53,462, filed August 31, 1925.

It is the main object of this invention to provide an improved pressed metal radiator construction of high efficiency.

10 Another object is to provide a radiator preferably constructed entirely of sheet metal having a large area of radiating surface, although extremely light in weight and requiring the circulation of only a small 15 volume of heating fluid therethrough.

It is a further object to provide an improved, pressed metal radiator construction requiring few parts and capable of being easily assembled to form a strong, compact 20 device.

Another object is to provide a simple and highly efficient means for closing the upper and lower ends of the several radiator cells and for forming the ends of the radiator 25 proper.

These and other objects of the invention will be apparent from the following description made in connection with the accompanying drawings wherein like characters 30 refer to similar parts throughout the several views, and in which

Fig. 1 is a side elevation of the preferred embodiment of the invention assembled.

Fig. 2 is an end elevation of the same.

35 Fig. 3 is a fragmentary vertical section on a larger scale taken on the line 3-3 of Fig. 1.

Fig. 4 is a cross section on a larger scale taken on the line 4-4 of Fig. 2.

40 Fig. 5 is a fragmentary plan view on a larger scale with a portion of the top cover broken away.

Fig. 6 is a detail vertical section on the line 6-6 of Fig. 5, and showing the means 45 for closing the ends of the several fins and the fitting of the top cover thereover, and

Fig. 7 is a fragmentary elevation of one of the end plates of the radiator detached.

In the drawings a preferred embodiment 50 of the invention is shown comprising in general the radiator proper or cell structure and a framework supporting the same at some distance above the floor.

The radiator proper is preferably entirely constructed of sheet metal comprising a 55 pair of longitudinal side members 8, each provided with a plurality of narrow, vertically spaced corrugations or fins 8^a, extending the entire height thereof. Fins 8^a are preferably spaced apart a distance over 60 three times the cross-sectional width of one of said fins and have substantially parallel sides. Side members 8 terminate at their 65 ends in outturned flanges 8^b disposed intermediate of the end fins 8^a thereon.

The ends of the radiator proper are formed by providing substantially rectangular plates 9 provided with outturned flanges 9^a disposed flush with flanges 8^b of the sides and welded or otherwise secured 70 thereto. The structure, therefore, has a pair of parallel vertically extending seams at either end thereof. End plates 9 are apertured adjacent the top and bottom edges and the material about the apertures drawn 75 outwardly to afford sleeves 9^b in which the internally threaded fittings 10 are welded or soldered, thereby efficiently securing said parts together. The fittings 10 are of course adapted to receive the threaded ends of the 80 supply pipes or plugs, as the case may be, upper and lower entrances to the radiator structure being provided at each end thereof for convenience and for reversal of the direction of the circulation without changing the position of the radiator.

The fins 8^a on the two sides 8 are oppositely disposed when the parts are assembled, cooperating to form a plurality of narrow cells *a* interconnected by a plurality 90 of unrestricted passages *b* extending the full height of the radiator proper. The relatively wide spaces between the several fins 8^a form relatively wide vertical air passages *c* 95 extending from the bottom to the top of the radiator.

The upper and lower ends of fins 8^a are closed, preferably effected by crimping the edges thereof, as shown in Figs. 5 and 6 and leaving elongated, substantially rectangular 100 openings extending centrally of the radiator structure at top and bottom. To close these rectangular openings I provide elongated channel members 11 which are inset 105 in said openings, the sides thereof being disposed flush with the edges of the radiator

- sides 8. Radiator sides 8 are drawn slightly outwardly, there being sufficient material in the curved upper and lower portions to form straight edges in connection with the inner edges of the crimped closed ends of fins 8^a (see Figs. 3 and 5). The edges of channel members 11 are then easily welded to the straight edges thus formed, thereby effectively closing the top and bottom.
- 10 To reinforce the radiator proper and also assist in the mounting thereof on a suitable frame above the floor, I provide a pair of tie rods 12 having flat body portions and terminating in threaded end portions 12^a.
- 15 Tie rods 12 are disposed centrally of the radiator structure, extending through the passages 6 and through the end plates 9, the threaded end portions 12^a being welded or soldered to end plates 9. Preferably 20 small sleeves are struck up in said end plates, similar on a smaller scale to the sleeve 9^b struck up to secure fittings 10. As shown in Fig. 1, the tie rods 12 are disposed horizontally through the top and bottom portions of the radiator structure.
- 25 I prefer to support the radiator on a pair of frame ends 13, which may be constructed also of sheet metal pressed to form the outwardly extending grooves 13^a adapted to 30 house the vertical seams at the radiator ends. Frame ends 13 are each provided with apertures adjacent top and bottom to accommodate the fittings 10, and sleeves 13^b are formed from the stock of said frame ends 35 by drawing the same outwardly about the apertures. Horizontal webs 13^c are pressed out extending from the corrugated groove portions 13^a of the frame ends to the sleeves 13^b. The threaded ends of tie rods 12 extend 40 through frame ends 13 and have secured on the outer sides thereof bolts 14 clamping the radiator structure within the frame. Legs 15 are formed in the lower portions of each of the frame ends 13 and the stock between the legs 15 is cut horizontally and turned inwardly to afford the supports 15^a disposed below the end cells *a*, and cooperating to support the radiator structure.
- 45 A top or cover 16 is provided for the radiator, formed preferably from a single rectangular blank of material. A plurality of substantially rectangular perforations are made in said blank on either side of the longitudinal center line thereof, corresponding to the air passages *c* between the several fins. The edges of the blank are drawn downwardly, as are the edges about the several perforations, forming depending flanges 50 which snugly engage the crimped edges *y* of the several fins and the ends thereof.

The process of making my radiator is substantially as follows:

I first form the side members 8, preferably by pressing rectangular blanks of sheet

metal into the form illustrated in the drawings. Side members 8 are then held in forms and spaced properly apart. The end plates 9 are then formed as described, having the out-turned flanges 9^a; and the fittings 10 are welded or otherwise secured to the sleeves 9^b, all before the ends and sides are assembled. With side members 8 spaced properly apart, the end plates are secured therebetween by welding the seams between flanges 8^a and 9^a. In forming the side members 8 the upper and lower horizontal edges are drawn slightly outwardly as indicated in Fig. 3 by the letter *x*. The upper and lower ends of the several fins 8^a are next closed by crimping the opposite edges thereof and welding the crimped seams *y* (see Figs. 5 and 6), thus leaving the elongated rectangular openings in the top and bottom. Since the stock of the sides 8 is drawn outwardly 85 slightly, the adjacent edges of the crimped portions *y* lie in substantially the same line therewith and permit channel members 11 to be inset within said rectangular openings with the sides thereof lying flush against the 90 sides of said openings. I then with little effort can weld the seams between the edges of said channel members and the sides and crimped portions of the fins. The ends of the channel members 11 are also welded to 95 the end plates 9.

The threaded ends of the tie rods 12 are welded in the end plates 9 and the radiator proper is then mounted in the frame ends 13 supported by means of the outwardly projecting fittings and the tie rods, and also by the inturned lower portions 15^a adjacent the legs of the frame ends. The nuts 14 are applied to the projecting threaded ends of the tie rods thereby clamping the radiator proper within the frame.

This novel process enables me to manufacture my device at little expense and assemble the same quickly. The ends and sides can be accurately made in the separate sections and the fittings may be secured before the parts are assembled. All of said parts can be stamped by machinery and the top and bottom of the radiator may be easily closed by means of the elongated channel members employed. The seams between all of the several parts are securely welded together and flanges are provided which make the welding an easy process.

The narrow cells *a*, having wide parallel radiating surfaces in combination with the wider passages interconnecting the same and extending the full height of the radiator structure, provide a radiator of high efficiency. The circulation between the several cells is unrestricted and it may be seen that only a small amount of heating fluid is required. The end frames and tie rods clamp the radiator therebetween, reinforcing the same against the pressure of 130

the heating fluid and moreover supporting the device the proper distance above the floor.

From the foregoing description it will be seen that I have invented an improved radiator construction and process for making the same capable of being manufactured at little expense and constructed preferably of sheet metal throughout.

10. It will of course be understood that various changes may be made in the form, details, proportions and arrangement of parts without departing from the scope of the invention.

15. What is claimed is:

1. A radiator structure comprising spaced side members each having a plurality of substantially vertical outwardly projecting hollow fins and each having outwardly extending vertical flanges as its ends disposed intermediately of the end fins thereof and at right angles thereto, and members connecting said sides, each comprising a plate provided with outwardly extending flanges secured to the flanges of said sides, said plates being recessed, and fittings secured within said recessed portions, and means for closing the top and bottom of said structure.

2. Radiator structure comprising a pair of oppositely disposed spaced sides each having a plurality of vertical outwardly projecting spaced hollow fins, flat end members connecting said sides and extending the full height thereof, means for closing the upper and lower ends of said fins, the material between said fins at the top and bottom of the structure being extended outwardly to form substantially continuous rectilinear edges at the top and bottom of the structure, said edges defining with said end members rectangular openings, and channel members having upturned longitudinal welding edges

inset between the rectilinear edges of said sides and having their end edges abutting said end members.

3. Radiator structure comprising a pair of oppositely disposed spaced sides each having a plurality of vertical outwardly disposed relatively narrow hollow fins formed therein, said channels of said two sides being oppositely disposed in pairs, the upper and lower ends of said channels being closed, flat end members connecting said sides and extending the full height thereof, and the material between said channels extending outwardly and rectilinearly at the top and bottom of the structure to afford rectilinear welding edges defining with said end members rectangular openings in the top and bottom of the structure, and channel members having rectilinear upturned longitudinal edges adapted to be inset within said first mentioned rectilinear welding edges, said edges being welded together and the end edges of said channel members being welded with said flat end members.

4. Radiator structure having in combination sides, each having a plurality of substantially vertical outwardly projecting hollow fins, ends connecting said sides having apertures therethrough, fittings for connection to a circulating system secured to the apertured portions of said ends and projecting outwardly therefrom, means for drawing said ends together, frame members at either end of said structure having legs at their lower ends adapted to support said sides and ends above the floor and portions of said frames adjacent their lower extremities being cut and turned inwardly to engage the under side of said ends for supporting the same.

In testimony whereof I affix my signature.
CARL S. CARLBERG.
